INVENTOR:
HARRY ZIMMERMAN
BY *Maurice Block*
ATTORNEY

UNITED STATES PATENT OFFICE

2,393,445

WHISTLING TOY

Harry Zimmerman, New York, N. Y.

Application December 2, 1944, Serial No. 566,300

4 Claims. (Cl. 46—179)

My invention relates to sound producing toys. An object of my invention is a toy that produces a whistling sound when jerked.

Other objects are a toy containing a voice, whistle or any sound producing device operated by draught of air, to create this draught of air by the movement of a piston in a cylindrical space of the toy, and to cause this movement by jerking the toy, thereby avoiding the use of a gear or of machinery for driving the piston and operating the voice.

Further objects are to provide a toy having two parts which move relatively to each other by the inertia of one of these parts when the other part is jerked, to create an air suction by this relative movement, and to operate a sound producing device by this air suction.

Still other objects are a toy of this kind which has handy means adapted to jerk the toy or to move it quickly or adapted to move the toy reciprocatingly or to make the toy oscillate, and a toy of this kind containing resilient means damping or softening the impact of the piston at the end of a stroke, and resilient means causing the piston to reverse its moving direction and causing the piston to return to its original position when the jerking operation ceases.

Still further objects are to produce a toy of this kind in which the maximum simplicity of construction and operation is secured, and to attain a surprising effect by this very simplicity.

Still further objects and advantages will appear from the following description of exemplifying embodiments of the invention, from the appended claims, and from the drawing in which:

Fig. 1 shows a longitudinal central cross-section through an illustrative embodiment.

Fig. 2 shows a cross-section through the same embodiment, said cross-section being taken along the line 2—2 in Fig. 1.

Fig. 3 shows a longitudinal side elevation of another illustrative embodiment.

Fig. 4 shows the latter embodiment seen from the upper side in Fig. 3.

Most of the parts used in the embodiment shown in Figs. 1 and 2 are identical to parts used in the embodiment shown in Figs. 3 and 4. With respect to these identical parts, Figs. 1 and 2 may be regarded as complements of Figs. 3 and 4, and vice versa.

Referring to the drawing, numeral 1 indicates a casing or outer body which may be cylindrical and may comprise a main body and a cover 2. An inner body or piston 3 is slidably inserted in the body 1 and has a hole passing through the body 3

in the sliding direction. This hole is filled with a sound producing device which may be constituted by a capsule or hollow member 4 or may have any other suitable structure operated by air passing from one side of the piston 3 to the other.

The capsule 4 contains a hollow space connected by a hole 5 to one side and by a hole 6 to the other side of the space in which the piston slides whereby movement of the piston will drive or suck air through the capsule and, thereby, produce a whistling noise. The capsule may be composed of two parts shaped like cylindrical cups having bottoms containing the holes 5 and 6 respectively and having side walls tightly contacting each other.

Preferably, the cover 2 has a number of holes 7, and similar holes 8 may be provided in the wall of the casing 1 and may be positioned near the edge of the cover 2. This edge forms a stop for the movement of the piston 3 in one direction. In the other direction, a similar stop may be formed by a cylindrical ring 9 inserted in the casing 1. The air contained in the inner space of the ring 9 together with the air in the recess 10 of the piston 3 forms a cushion which is resiliently compressed or dilated when the piston reciprocates and contributes to the efficiency of the air current operating the whistle 4 while, at same time, softening the stroke of the piston against the ring 9. This stroke may be further softened by a resilient cover of the stopping edge of the ring 9, for example by a cord 11 laid over the stopping edge and having ends wedged between the walls of the ring and of the casing 1.

The parts which have been described so far may be used identically in both illustrated embodiments. The two embodiments differ merely in the means to create inert forces causing the piston and the casing to move relatively to each other.

In the embodiment shown in Figs. 1 and 2, the inner body 3 is jerked, and the outer body 1 lags due to its inertia. The jerking pull may be transmitted to the piston 3 by a cord or string 12 passing from the open into the casing 1 through a hole 13 and having an inner end affixed to the piston in any suitable manner. For example, a wire 14 may have ends wedged into the piston and may form a bridge in the center of which the string 12 is attached by means of a knot 15. The hole 13 may be surrounded by a guide ring 16 riveted to the cover 2.

A spring 17 may be wound around the inner part of the string 12 and may be compressed by the impact of the moving piston 3. This spring tends to reverse the moving direction of the pis-

ton and to bring it back to its original position in which the piston contacts the cord 11.

In the embodiment shown in Figs. 3 and 4, the outer body 1 is jerked, and the inner body 3 lags due to its inertia. The casing 1 may be moved by means of a handle 18 affixed to the casing and having, preferably, a direction crossing the direction of the sliding movement. This handle facilitates the creation of a quick movement and the production of a loud noise. The handle may be moved or reciprocated in any desired direction while, in the first described embodiment, the casing is suspended and will make leaping movement in a substantial vertical direction.

In both embodiments, the piston 3 divides the inner space of the casing into two parts, partitioning off a partial space surrounded by an uninterrupted or solid part of the casing's wall and having no other outlet than the hole 6 whereby the air confined in this part is forced vehemently through the whistle 4 when the piston 3 moves relatively to the casing. Preferably, that part of the casing's wall which borders or surrounds the space positioned at the other side of the piston has perforations, for example the holes 8, permitting air and sounds to pass into the open.

The bodies 1 and 3 are free to fly between the end stops under the influence of inert and resili-ent forces, these bodies being free from any other kinematic connection than the contact of their sliding surfaces, no gear or machinery being used to enforce their relatively sliding movement.

I desire it understood that my invention is not confined to the particular embodiments shown and described, the same being merely illustrative, and that the invention may be carried out in other ways without departing from the spirit of my invention as it is obvious that the embodiments shown and described are only a few of the many that may be employed to attain the objects of my invention.

Having described the nature of my invention

and how it operates, what I claim and desire to secure by Letters Patent is:

1. A sounding toy comprising a hollow body member, a piston member slidably mounted within the hollow body member and movable therein from end to end, an air duct extending through said piston member from one face thereof to the other for air flow therethrough as the piston moves within the hollow body member, spring means urging said piston member in one direction, manual means attached to one of said members for quickly moving one of said members relative to the other and against the force of said spring means, and an air operated sounding device operable by air flow in either direction there-through mounted on the piston member within the air stream flowing through said duct when said members are relatively moved.

2. A sounding toy of the character described in claim 1 wherein the manual means comprises a handle connected to said hollow body member with the axis of the handle generally transverse to the path of movement of the piston within said hollow body member.

3. A sounding toy of the character described in claim 1 wherein said manual means comprises a flexible strand connected to said piston member and wherein said spring means urges the piston member into the lower end of said movable member.

4. A sounding toy of the character described in claim 1 wherein said spring means urges said piston to one end of said hollow body member, and wherein said manual means is a flexible strand attached to said piston member and operable to move the piston member against the force of said spring away from said one end of the hollow body member, and guide means carried by the opposite end of said hollow body member and through which said flexible strand passes.

HARRY ZIMMERMAN.
